[57] CLAIM

The ornamental design for a golf bag cooler pack, as shown and described.

DESCRIPTION

FIG. 1 is a top, front, and left side perspective view of a golf bag cooler pack with the top cover raised, showing my new design;

FIG. 2 is a sectional view along the line 2—2 of FIG. 1; FIG. 3 is a front elevational view thereof;

FIG. 4 is a right end elevational view thereof, the left end elevational view being substantially the mirror image thereof without the handle; and

FIG. 5 is a top plan view thereof, the bottom plan view being substantially the same.

The cans shown in broken lines in FIG. 1 are for illustrative purposes only.
